(21) Appl. No.: **29/353,381**

CLAIM

(22) Filed: **Jan. 7, 2010**

(57)

(51) **LOC (9) Cl.** 08-08

DESCRIPTION

(52) **U.S. Cl.** D8/388; D25/133

FIG. 1 is a top view of the anchor post of the invention; FIG. 2 is a perspective view of the anchor post shown in FIG. 1;

(58) **Field of Classification Search** D8/388,

FIG. 3 is an underside view of the anchor post shown in FIG. 1;

D8/354; D21/840; D25/131, 133; 248/530,

FIG. 4 is a front view of the anchor post shown in FIG. 1; FIG. 5 is a side view of the anchor post shown in FIG. 1; and, FIG. 6 is a rear view of the anchor post shown in FIG. 1.

248/156, 87; 52/153, 155, 704

See application file for complete search history.
